VENETIAN BLIND AND BRACKET THEREFOR

Hugo C. La Ganke, East Cleveland, Ohio

Application October 24, 1938, Serial No. 236,604

10 Claims. (Cl. 156—17)

My invention relates to Venetian blinds and more particularly to an improved bracket for supporting the head rail of such blinds.

In the installation of Venetian blinds in homes or office buildings it is highly desirable to firmly anchor the head rail in position. Otherwise, the wind, or the movement of conveyances, such as streetcars or heavy trucks past the building, has the tendency to set up vibrations in the head rail which is transmitted to the tilt rail and adjacent slats and causes rattling of the blinds.

The aim of the present invention is to provide improved means for fastening the ends of the head rail of Venetian blinds in place and for this purpose I have provided a pair of brackets, one of which is adapted to be secured to one side or the front of a window frame and the other of which is adapted to be secured to the opposite side or front of the window frame, said brackets being provided with recesses to receive the opposite ends of the head rail and with means for securely fastening the head rail in place.

Another object of my invention is to provide an improved bracket for Venetian blinds which may be economically manufactured by a simple stamping and forming operation and which is provided with a recess to receive one end portion of a head rail which may be of various out widths, means being also associated with the bracket for securely anchoring the head rail in place.

A further object of my invention is to provide an improved bracket for Venetian blinds provided with a recess to receive one end portion of a Venetian blind and in which head rails of various widths may be inserted, securely fastened in place, and easily removed when desired.

My invention will be better understood by reference to the accompanying drawing, in which

Fig. 1 is a front elevational view of a Venetian blind showing the opposite ends of the head rail extending into recesses in brackets fastened to the opposite sides of a window frame;

Fig. 2 is a perspective view of my improved bracket showing the securing device in its inoperative position;

Fig. 3 is a cross sectional view on the line 3—3 of Fig. 2, showing the end of the head rail in position in the recess formed in the bracket, the securing device being in its operative position; and

Fig. 4 is a cross sectional view on the line 4—4 of Fig. 3, showing one means of attaching the securing device to the bracket.

Referring to Fig. 1 of the drawing, a Venetian blind of the usual construction is illustrated, including a head rail 1, a tilting rail 2, and a plurality of slats 3 which are connected together and to the tilting rail by tapes 4. As in the usual construction, the bottom rail and the slats may be raised by cords 5 attached to a bottom rail, not shown, and extending through slats 3 and openings in the head rail. The slats may also be tilted to the desired angle by any convenient means. As illustrated, a tilting device 6, which may be of any desired form, is secured to the head rail adjacent one end thereof and is provided with a trunnion 7 extending into an opening in one end of the tilting rail, the other end of the tilting rail being supported by a bracket 8 provided with an opening to receive a trunnion 9 extending from the opposite end of the head rail. As is usual in constructions of this type, the tilting rail 2 and the slats associated therewith may be adjusted to any desired angle by exerting a slight pull on one or the other end of cord 10.

From the construction thus described, it will be noted that the tilting rail 2 is connected to head rail 1 and consequently any movement or vibration of the head rail will be transmitted to the tilting rail and the adjacent slats, thereby causing rattling of the blind. In accordance with my invention, I have provided improved means for securely fastening the head rail to the window frame in such a manner that vibrations of the head rail may be minimized. For this purpose I have provided improved brackets 11 and 12 attached to opposite sides of the window frame, each bracket being provided with flanges which extend in a direction opposite to the flanges on the other bracket. Recesses are thus formed to receive the opposite ends of the head rail which may be secured in place by improved means to be presently described. As shown in Fig. 1 of the drawing, brackets 11 and 12 are similar, that is, they are complementary to each other and consequently only one of the brackets is shown in detail.

While my improved bracket may be formed of any desirable number of parts or of any desired material, for purposes of illustration, as indicated more clearly in Figs. 2 and 3, it consists of a sheet metal stamping of angular form, one leg of which is formed to provide an intermediate body portion 13, laterally extending flanges 14 and 15, and an end flange 16, the flanges forming a recess to receive the end portion of the head rail. From the structure thus

described it will be noted that the end portion of the head rail may be inserted between flanges 14 and 15 and is limited in its inner movement by the flange 16. The body portion 13 may be 5 of such a length that head rails of various widths may be inserted in the recess.

For the purpose of securing the end of the head rail firmly in position, the body portion is provided with a downwardly extending leg or arm 10 17 having an inwardly extending lug 18 which is parallel to the flange 16 and perpendicular to a plane passing through flange 15. As shown in the drawing, the lug 18 is spaced from one end of the flange 15 and the intermediate body portion 13 is provided with a notched opening 19 for permitting one arm of the securing device 15 20 to be forced into the portion of the wooden head rail extending into the recess.

While securing device 20 may be movably 20 mounted upon the leg portion 17 or upon the lug 18 in any desired manner to secure the end of the wooden head rail firmly in place, such as by means of a rivet or the like, as illustrated in Fig. 4 of the drawing, an annular flange is punched from securing device 20 a short distance from one end thereof as indicated by the numeral 21, which is inserted through an opening in lug 18, the outer end of the flange having a curled edge to provide a pivotal connection between securing device 25 20 and lug 18. A cutting portion 22 and a handle portion 23 are thus provided, the handle portion having a lug 24 by means of which it may be conveniently operated. As shown in the drawing, when the handle portion of the device is raised 30 sufficiently to permit the end portion of the head rail to be inserted in the recess formed by flanges 14, 15 and 16, the end of the cutting portion is substantially flush with the outer side of the body portion 13. After the end portion of the head 35 rail has been inserted in place, the handle 23 is moved downwardly, forcing the cutting portion 22 through the opening 19 and into the wood, cutting a groove in the portion of the head rail extending into the recess, and the weight of the handle will 40 have the tendency to maintain the end portion of the head rail firmly in the groove which has been cut. The fastening device may be released from the head rail when desired, by raising the handle portion of the device attached to each 45 bracket.

My improved bracket may be attached either to the side wall of the window frame as shown, or may be attached to the front wall of the frame. For this purpose the body portion 13 is provided 50 with apertures 25 through which screws may be inserted to attach the bracket to the side wall of the window frame, and flange 16 is also provided with apertures 26 through which screws may be 55 inserted to attach the brackets to the front wall 60 of the window frame.

What I claim is:

1. A bracket for supporting the wooden head rail of Venetian blinds, including a metallic frame formed of an integral metallic strip having upper 65 and lower inwardly extending flanges, an intermediate body portion, a side flange, and an inwardly extending lug parallel to said side flange and substantially perpendicular to a plane passing through the lower flange, said flanges forming 70 a recess to receive one end portion of said rail and the lower edge of the body portion being notched adjacent said lug to provide an opening leading into said recess, and a cutting device pivotally mounted on said lug in a manner to 75 provide a comparatively short cutting portion

and a comparatively long handle portion, said handle portion being adapted to be moved upwardly to afford access to said recess and downwardly to cut a groove in said rail, the weight of said handle acting by gravity to maintain the 5 cutting edge of said device in said groove.

2. A bracket for supporting the head rail of Venetian blinds, including a frame having parallel upper and lower laterally extending flanges and an intermediate body portion which form a recess 10 to receive the end of the head rail of a Venetian blind, said frame being provided with an opening below said recess, and means for securing said head rail in place including a substantially flat metal strip having an integral flange extending 15 through said opening and provided with a curled edge which frictionally bears against the walls of the frame but permits pivotal movement of said strip on said frame.

3. A bracket for supporting the head rail of 20 Venetian blinds including an angular member having a longitudinally extending leg and a downwardly extending leg, said longitudinally extending leg having an upper laterally extending flange and a lower laterally extending flange 25 which form a recess to receive the end of said head rail, said lower flange being of insufficient length to reach the downwardly extending leg, thereby forming an opening leading into said recess, and a securing device pivotally mounted 30 on said downwardly extending leg and being adapted to be rotated in a plane which is substantially perpendicular to the longitudinally extending leg and having a portion which is adapted to be moved upwardly through said opening to cut 35 a groove in said head rail which is substantially parallel to the longitudinal axis of said head rail.

4. A bracket for supporting the head rail of Venetian blinds including an angular member having a horizontally extending leg and a downwardly extending leg, said longitudinally extending leg having an upper laterally extending flange and a lower laterally extending flange which forms a recess for the end of said head rail, said lower flange being of insufficient length 40 to reach the downwardly extending leg, thereby forming an opening leading into said recess, and a securing device having a cutting portion and a handle portion pivotally mounted on the downwardly extending leg portion in such a manner 45 that it may be rotated in a plane substantially perpendicular to the horizontally extending leg portion, said cutting device being pivotally associated with the downwardly extending leg in such a manner that when the handle of the securing device is raised the cutting portion is lowered below said recess and when the handle portion is lowered the cutting portion is forced upwardly through said opening and cuts a groove in said head rail extending substantially parallel with the longitudinal axis of the head rail and the weight of the handle serves to hold the cutting portion of said device in said groove.

5. A bracket for supporting the head rail of 65 Venetian blinds, including an angular member having a horizontally extending leg and a vertical leg, flanges extending laterally from the opposite edges of the horizontally extending leg, a flange extending laterally from the end of the horizontal leg, said flanges forming a recess to receive one end of said head rail and the flange on the lower edge of the horizontally extending leg being of insufficient length to reach the vertical leg thereby providing an opening extending 70 75

into said recess, a lug extending inwardly from the inner side of the vertically extending leg and a securing device having a cutting portion and a handle portion pivotally mounted on said lug and being adapted to be rotated in a plane which is substantially perpendicular to a plane passing through said horizontal leg, the head portion of said securing device being adapted to be moved upwardly to enable the end of said head rail to 10 be inserted in said recess and being adapted to be moved downwardly to cut a groove in said head rail which is parallel to a plane passing through the horizontal axis of said head rail.

6. A bracket for supporting the wooden head rail of Venetian blinds including a frame having upper and lower inwardly extending flanges and an intermediate body portion which forms a recess to receive one end of the head rail, said frame being also provided with a portion extending inwardly below the normal level of the head rail having a device pivotally mounted thereon in a manner to form a short cutting portion and a longer handle portion, said device being arranged in such a manner with respect to said recess that when the handle portion of said device is moved upwardly free access is provided to said recess for insertion of the head rail and when moved downwardly the cutting portion of said device is forced into the portion of the head rail which lies in said recess, the weight of said handle serving to maintain the cutting portion of said device in the groove formed during the cutting operation.

7. A bracket for supporting the wooden head rail of Venetian blinds including a frame having upper and lower inwardly extending flanges and a side flange, said flanges forming a recess to receive the end of said head rail, a lug attached to said frame below said recess and a device pivotally mounted on said lug a short distance from one end thereof, one end of said device forming a cutting portion and the other end a handle portion, said device being arranged with respect to said recess in such a manner that when the handle portion of said device is moved upwardly the cutting portion of said device is moved out of said recess and free access is provided for insertion of the head rail therein, and when the handle portion of said device is moved downwardly and the head rail is in position in said recess the cutting portion of said device is forced into the bottom edge of the head rail located in said recess.

8. In combination with a head rail of a Venetian blind for windows, a pair of brackets, one of which is adapted to be attached to one side of a window frame and the other of which is adapted to be attached to the other side of said frame, each of said brackets having flanges forming a recess and which extend in a direction opposite to the flanges of the other bracket, one of said recesses being adapted to receive one end of the

head rail and the other recess being adapted to receive the other end of the head rail, each of said brackets having pivotally mounted thereon a device having a cutting portion and a handle portion, said device being mounted upon said brackets in such a manner with respect to said recesses that when the handles are moved upwardly free access is provided to said recesses for insertion of the ends of the head rail and when moved downwardly toward the respective sides of the frame on which the bracket is mounted and the head rail is in position with its end portions in said recesses, the cutting portion of each device is forced into the head rail extending into the recess of the bracket with which it is associated to form longitudinally extending grooves in said head rail which are in substantial alignment with each other, thereby maintaining the head rail firmly in position.

9. A bracket for supporting the head rail of Venetian blinds including an integral stamping having two legs, one of said legs having flanges extending laterally therefrom forming a recess to receive one end of said head rail and a securing device having a cutting portion and a handle portion pivotally associated with the second leg of said stamping in such a manner that it can be rotated in a plane substantially perpendicular to the first mentioned leg, said securing device being associated with said legs in such a manner that when it is rotated in one direction free access is provided to said recess for insertion of said head rail and when it is rotated in the opposite direction and the head rail is in place the cutting portion of said device is forced into said recess to cut a groove in said head rail which is substantially parallel with the longitudinal axis of the head rail.

10. A bracket for supporting the head rail of Venetian blinds including an angular member having a longitudinally extending leg and a vertically extending leg, said longitudinally extending leg having upper and lower laterally extending flanges, thereby forming a recess to receive the end of the head rail of the Venetian blind and a device having a handle portion and a cutting portion movably associated with the vertical leg in such a manner that it may be moved in a plane substantially perpendicular to the horizontally extending leg, said device being associated with said legs in such a manner that when the handle portion of said device is moved upwardly free access is provided for inserting a portion of the head rail in said recess and when the handle portion of said device is moved downwardly the cutting portion of said device is moved into said recess and cuts a groove parallel to the longitudinal axis of the head rail thereby firmly securing said head rail in said bracket.

HUGO C. LA GANKE. 60
